UNITED STATES PATENT OFFICE

105,932

DESIGN FOR A BARREL

Lewis T. Baker, Jacksonville, Fla.

Application June 18, 1937, Serial No. 69,904

Term of patent 7 years

To all whom it may concern:

Be it known that I, Lewis T. Baker, a citizen of the United States, residing at Jacksonville, in the county of Duval and State of Florida, have invented a new, original, and ornamental Design for a Barrel, of which the following is a specification, reference being had to the accompanying drawing, forming part thereof.

I claim:

The ornamental design for a barrel, as shown.

LEWIS T. BAKER.
